UNITED STATES PATENT OFFICE.

WILLIAM WESTBURY, OF CANEY, KANSAS.

WINDOW-GLASS APPARATUS.

Application filed February 19, 1923. Serial No. 619,927.

To all whom it may concern:

Be it known that I, WILLIAM WESTBURY, a citizen of the United States, and resident of Caney, county of Montgomery, State of Kansas, have invented a certain new and useful Improvement in Window-Glass Apparatus, of which the following is a complete specification.

This invention relates to window glass apparatus. At the present time two methods of drawing glass cylinders by what is known as the pot method, are employed. In one method, one of a pair of pots, is inverted into a kiln at the top thereof to melt the hardened residue of glass from the pot, while a cylinder is being "pulled" from the companion or upright pot. In the other method one of a pair of pots is supported "on edge" and faces into a kiln through an opening 10 in one side thereof to effect the melting and drainage of glass from such pot, the companion pot being upright at the time so that a cylinder can be "pulled" therefrom. In each of the kilns of such methods, there is 15 a drain hole, and two burners for heating purposes, and the proportions of the pots with respect to the kiln are such that the temperature of the latter is unduly lowered by the burning-out operation, which is therefore retarded until the normal temperature 20 is restored.

This is one drawback to the use of an individual pot kiln, and another is that neither oil nor producer gas—especially the latter—can be used efficiently with such small kilns, and a blast to give full and quick heating results, is destructive of the walls of the kiln and of the pots.

My object therefore is to provide a kiln 40 of such size and proportion as to accommodate a plurality of pots so that the burning-out of the cold or residue glass from one or more pots at the same time shall not unduly lower the temperature and therefore efficiency of operation or retard the same.

A further object is to provide a kiln for accommodation of a plurality of pots, having provision for reversing the points of supplying the fuel from one end or side of the kiln to the other at regular intervals, so that the kiln may be maintained at a uniform temperature at all points and at all times, a further object being to provide a kiln in which gas, oil or producer gas may

be efficiency employed. With a kiln of this character, there will be no material fluctuation of temperature due to exposure in the kiln of cold glass in a pot or any necessity for suddenly raising the temperature by means of a blast, to restore the kiln to normal temperature, which sudden changes of temperature are very destructive on the walls of a kiln and on the pots, and furthermore results in more or less unevenness in the thickness of the walls and in the diameter 55 of the glass cylinders which are "pulled."

With these objects in view the invention consists in certain novel and useful features of construction and combinations of parts as hereinafter explained, and in order that it may be fully understood, reference is to be had to the accompanying drawing, in which:

Figure 1 is a perspective view of a kiln embodying the invention;

Figure 2 is a horizontal section of the same taken on the line II—II of Figure 1;

Figure 3 is a cross-section of the kiln equipped with a pot carrying and adjusting means for supporting a pair of pots, one from which a cylinder is to be pulled and the other from which the cold or residue glass is melted into the kiln; and

Figure 4 is an enlarged vertical longitudinal section of the kiln.

Referring now to the drawing in detail, 1 indicates a flooring below which is located a kiln 2 provided with a drain hole 3, and communicating with opposite ends of the kiln are ducts 4 and 5, the opposite ends of the ducts communicating with a flue 6 leading to a stack 7, the front end of the flue being open as at 8 to provide an intake for air.

A butterfly valve or the like 9 is located at the junction of the ducts 4 and 5 with the flue 6 so that it may be adjusted for establishing simultaneous communication between one of the ducts and the stack and between the intake of flue 6 and the other duct, and to control the draft, a damper 10 is located in the flue 6 between the points of communication therewith of the ducts 4 and 5 and the stack.

For the purpose of heating the air which enters the flue from the ducts, checker work 11 of suitable material is located in each of the ducts. Communicating with the duct

5 adjacent the kiln, is an additional duct 11^a, provided with a similar checker work 11^b, and said duct communicates at its opposite end with the flue 6 rearward of the 10 butterfly or equivalent valve 9. The duct 11^a is controlled by a damper 12, and a supply pipe 13 for producer gas or the like communicates with the duct 11^a between the damper thereof and the kiln, and is controlled by a valve 14. If the kiln is to be operated reversibly with producers gas, the arrangement described must be duplicated at the other end of the kiln in conjunction with duct 4 as shown and described in connection with duct 5.

15 is a supply pipe for natural gas communicating with duct 4 and controlled by a valve 16. As shown, an oil supply pipe 17 is arranged, in conjunction with duct 5. 20 It will thus be seen that if natural gas only is available, it can be supplied at either end of the kiln so as to be possible to reverse the fire at suitable intervals, and the same statement applies with respect to the burning 25 of oil. This statement is also true with respect to the burning of producer gas, provided the same equipment shown in conjunction with duct 5, is supplied in conjunction with duct 4. With the valves arranged as 30 shown in Figure 2, it is obvious that the fuel of combustion will be supplied to the kiln from duct 5, the air to support combustion, especially if natural gas is used, entering at the intake point 8, while the products 35 of combustion will pass out of duct 4, and in so doing will heat the checker work therein, and pass from duct 4 into flue 6 and to the stack. By reversing the butterfly valve the air can be supplied through duct 4 to 40 support combustion through the burner therein and the products of combustion will pass through duct 5, heating the checker work therein and then pass to the flue and thence to the stack. It will thus be seen that 45 the checker work of the ducts is available for heating the air at all times.

With a kiln of the character described, it will be most convenient to use four double pots as one blower can handle four machines. 50 Of course, the kiln may be adapted to handle a fewer number of machines or pots or a greater number, and in this connection it may be stated that if oil is used for the fuel, it will be desirable to line the 55 walls of the kiln with silica brick as they will stand the oil fire better than the fire clay commonly used. However, the particular composition of the walls of the kiln or of the pots is not material in this invention, as any suitable type of material may 60 be employed.

The kiln may be provided with openings 65 18 either in one side as shown, or in the top. If the openings are provided in the side of the kiln, it is essential that each member

of the double pot shall be capable of adjustment so as to occupy an upright position when a cylinder is being drawn therefrom and an edgewise position when the residue of glass is being melted from the pot. As 70 one convenient method of supporting and adjusting a double pot of the character last referred to, I employ a shaft 19 which is suitably journaled transversely of the kiln and vertically over each opening 18. A 75 lever is employed identified by the character 20, for shifting said shaft longitudinally without interfering with free rotative movement thereof when necessary. The lever is fulcrumed upon a support 21 equipped with 80 a sector 22 for engagement by a latch mechanism 23 carried by the lever, so that the shaft can be secured at the desired point of longitudinal adjustment.

A suitable frame 24 is mounted upon the 85 shaft and projects up through an opening 25 in the flooring. At diametrically opposite points the frame is equipped with a pair of pots 26 which are pivotally mounted so as to be capable of assuming an upright position or an edgewise position, and as a simple way of supporting the pots in an upright position adjustable rods 27 are provided. Any suitable means may be provided for rotating the shaft after it has been 90 adjusted so that the pots will clear the kiln, to raise the lower pot to an upright position above the flooring and lower the other pots to a position opposite the openings 18 in the wall of the kiln and to dispose such pots in an edgewise position, after 95 which the lever is adjusted to shift the shaft so as to cause said edgewise arranged pots to enter the openings and be subjected to the heat of the kiln in order that the glass in the pots may be melted therefrom and drain into the kiln. The special construction of this type of double pot and the means for adjusting it are embodied in a 100 copending application and for this reason the said construction and its mode of operation have not been detailed with any great or sufficient particularity.

From the above description it will be apparent that I have produced a kiln embodying the features of advantage set forth as desirable in the statement of the object of the invention, and while I have illustrated the preferred construction it will be understood that it is susceptible of modification in various particulars without departing from the principle of construction or mode of operation involved.

I claim:

In glass making apparatus, a kiln having a plurality of openings, conduits communicating at one end with the kiln at opposite points thereof, a flue connected to the opposite ends of the conduits and open at one end, a stack connected to the other 125 130

end of the flue, a valve for establishing communication between the rear end of either of the conduits and the open end of the flue and between the rear end of the other conduit and the stack, means for discharging a combustible mixture into the kiln from the conduit in communication with the open

end of the flue, to sustain combustion in the kiln, and means for facing pots in the kiln through the openings of the latter. 10

In witness whereof I hereunto affix my signature.

WILLIAM WESTBURY.
